ROTARY INTERNAL COMBUSTION ENGINE
Robert C. Geschwender, Lincoln, Nebr., assignor to Lancaster Research and Development Corporation, Lincoln, Nebr., a corporation of Nebraska
Filed May 17, 1961, Ser. No. 110,735
11 Claims. (Cl. 123—16)

This invention relates to rotary internal combustion engines, and more specifically to engines of this type in which all piston-forming elements have a fixed angular relationship.

Among the several objects of the invention may be noted the provision of an internal combustion engine of the rotary type in which the pistons are carried in fixed angular relationship to one another upon a single rotor, and in which reciprocating sliding vanes which are piston components have their reciprocating movements accurately and positively controlled by positive-drive linkages, and more particularly by so-called slider-crank linkages driven by planetary gear trains, whereby a substantial amount of sliding friction is avoided; and the provision of an engine of this class which is comparatively simple to construct, and efficient and reliable in operation. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

FIG. 1 is an end view of the engine, with parts broken away to show various features in different fragmentary cross sections;

FIG. 2 is an axial section taken on line 2—2 of FIG. 1;

FIG. 3 is an exploded view in isometric form, showing a rotor, its end plates, one vane therefor, and one planetary gear;

FIG. 4 is an isometric view of a blocking rotor; and

FIGS. 5, 6 and 7 are cross sections taken on lines 5—5, 6—6 and 7—7, respectively, of FIG. 2.

Corresponding reference characters indicate corresponding parts throughout the several views of the drawings.

Details of various running seal means are not elaborated herein because they will be of appropriate spring-pressed varieties known to the art. For convenience in identification they are arbitrarily illustrated by stippling.

In the isometric views (FIGS. 3 and 4), several teeth only are shown on the several gears illustrated. It will be understood from the remaining drawings that each of these gears has teeth throughout its periphery and that the single planetary gear shown is illustrative of twelve of the same actually used.

The term oval will hereinafter be used generically to designate a bisymmetrical form like, or identical with, an ellipse, having comparatively long and short axes.

Briefly, the engine comprises a casing forming an inner chamber in which is located a circular main rotor carrying radially slidable vanes, the outer margins of which (except as to certain sealing parts) follow (but are not

2

directly constrained by) the chamber form. The arrangement is such as to provide expandable chambers for carrying out intake, compression, explosion and exhaust events of a four-cycle energy-conversion process. 5 The slidable vanes are reciprocated by positive-drive, so-called slider-crank mechanisms having the usual advantages of pin-type linkages. Each slider-crank mechanism is driven by a planetary gear means meshed with coaxial sun gear means affixed to the casing. An auxiliary blocking member cooperates tangentially with the main rotor for the purpose of dividing intake and exhaust spaces. This blocking member is preferably in the form of a rotor driven by a gear attached to the main rotor and meshing with a pinion which drives the blocking rotor.

Referring to the drawings, and more particularly to FIGS. 1-3, there is shown at numeral 1 a casing consisting of a central ring 3, the inside of which has an oval contour 5 of bisymmetrical shape on perpendicular short and long axes X—X and Y—Y. At 7 and 9 are shown 10 intake and exhaust pockets, respectively. These pockets 7 and 9 are narrower in an axial direction than the width of the surface 5 of ring 3. The ring 3 is flanked by attached end plates 11 and 13, respectively. These provide annular end pockets 15 and 17, surrounding central bearings 19 and 21 of plates 11 and 13, respectively.

At numeral 23 (FIG. 3) is shown a circularly symmetrical rotor mounted upon a power shaft 25, the latter being supported in the bearings 19 and 21. It, with the oval form of surface 5 establishes two opposite crescent-shaped spaces extending across the long axis Y—Y joined by smaller spaces extending across the short axis X—X. The rotor has six radial slots 27 located at 60° intervals, each slot being for the reception of a slidable T-shaped vane 29. The width of the upper cross-over portion 31 of each vane 29 equals the rotor width. Opposite sides of the rotor 23 contain recesses 33. Stem portions 35 of the T-shaped vanes 29 have widths equal to the rotor width between the bottoms of the rotor recesses 33. Seals 37 in the rotor 23 engage opposite faces of the vanes 29. Gudgeon pins 39, which extend from the opposite sides of the stem 35 of each vane 29, are located for movements in the opposite recesses 33.

Bolted to the right side of the rotor 23 (FIGS. 1-3) is a circular plate 41 in which is an opening 43 surrounding bearing 21. This ring 41 contains an inside pocket 45 for the reception of six gudgeons 47 extending toward the rotor 23.

Bolted to the left side of the rotor 23 is another ring 49 which also contains a pocket 45', like pocket 45 in ring 41 (see FIG. 2). Ring 49 also carries a set of six gudgeons 47', coaxial with the gudgeons 47 in plate 41. On each of the gudgeons 47, 47' is a rotary planetary gear 51. These mesh with and roll around fixed sun gears 53. The sun gears 53 are coaxially positioned around bearings 19 and 21 of the casing 1. Each planetary gear 51 carries a gudgeon pin 55. The gears 51 are so phased that the gudgeon pins 55 are coaxial by pairs in the opposite spaces 33. At numerals 57 are shown connecting links, each of which connects one pair of gudgeon pins 39 and 55.

When the rings 41 and 49 are attached to the rotor and the resulting assembly located in the casing 1, the outer margins of the rings 11 and 13 have running fits with respect to the circular portions of the pockets 15 and

17, respectively. Attachment is made by bolts such as 2 (FIG. 2) passing through holes such as 4 and threaded into holes 6 in the rotor (see also FIG. 3). Ring seals 59 are provided in suitable grooves in the rings on plates 41 and 49 to resist leakage at these running fits. It will be noted from FIG. 2 that the inner faces of the rings 49 and 41 are flush with the inner faces of the plates 11 and 13, respectively, to produce sidewise coplanar surfaces for running cooperation with the opposite flat ends of the T-heads 31 of the vanes 29.

Sealing strips 61 are provided in grooves along the sides and outer margins of the T-heads 31 of vanes 29. It will be apparent that the outer strips of the sealing strips 61 cannot escape from their vanes 29 in passing over the intake and exhaust pockets 7 and 9 because the latter are narrower in an axial direction than the width of surface 5 and narrower than the widths of the T-head portions 31.

In view of the above, it will be seen that upon turning of the rotor 23, the planetary gears 51 mesh with and roll around the sun gears 53, to reciprocate the vanes 29 in the rotor 23. Reciprocation occurs by means of the slide mechanisms constituted by the gudgeon pins 55 on gears 51 acting as cranks, the vanes 29 with their gudgeon pins 39 acting as sliders and the links 57 acting as connecting links between the gudgeon pins of the cranks and sliders. It is in this sense that the term slider-crank mechanism is used herein as defining the means for coupling the gears 51 and the vanes 29, in order to reciprocate the latter. The numbers of teeth selected for the planetary gears 51 and the sun gears 53 are in the ratio of 1:2 (24 and 48 teeth, respectively). Therefore, each planetary gear 51 drives its respective vane 29 inward and outward twice per revolution. The resulting oval trajectory of the outer margin of each vane defines the shape along which the inner surface 5 of the ring is machined with a slight clearance. Centrifugal force does not force the outer margins of the vanes 29 into engagement with the slightly clearing oval inner face 5 of member 3. Only the outer packing strips 61 are so forced to close the gaps due to clearance. The oval forms of the face 5 and trajectories of the outer vane margins are in the nature of closely coincident ellipses. The result is a construction by means of which comparatively small spaces are formed between the oval inside of the ring 3 and the circular rotor 23 at opposite ends of the small diameter of the oval, and comparatively larger spaces at opposite ends of the large perpendicular diameter of the oval.

The left-hand ring 49 is constructed with an integrated gear 63 which meshes with a pinion 65 attached to a blocking cylinder 67 (see FIG. 4). Cylinder 67 rotates in a cylindrical portion 69 bored out in the lower portion of ring 3. At 8 and 10 it is necked down to fit in holes 12 and 14 of rings 11 and 13, respectively. Packing rings 16 and 18 are employed in necks 8 and 10, respectively. From necks 8 and 10 extend gudgeons 71 and 73, the former being carried in a bearing in a cover plate 75 bolted to plate 11, and the latter in a bearing in plate 13. The upper part of the cylindrical portion 69 in ring 3 is open. Flanking portions 79 are shaped to coincide with the inner oval form 5. Thus an upper part 81 of the cylinder 67 extends out across the small space 83 into tangency with the outer surface of the rotor 23. A pair of opposite axial grooves 85 in the blocking cylinder 67 are adapted upon rotation to admit and pass ends of successive vanes 29. The grooves have appropriate trochoidal cross sections adapted to admit and pass the vane ends in approach and recess actions without interference.

The tooth ratio between gears 63 and 65 is 3:1, as for example, 120 teeth on gear 63 and 40 teeth on gear 65. Thus for one revolution of the main rotor 23, six vane ends will pass a tangent point 81 in conjunction in each instance with the passage of a cooperating groove 85. Therefore, regardless of the rotor position, the intake pocket 7 will always be separated from the exhaust pocket 9, either by a condition of tangency between the cylinder

5 drical faces between the main rotor 23 and auxiliary rotor 67, or by the position of a passing vane end in a passing groove 85.

5 As will be noted from FIG. 1, an intake port 87 communicates with the intake pocket 7, and an exhaust port 89 communicates with the exhaust pocket 9. It is assumed that a suitable carburetor system is connected with the intake 87, to carburet air with fuel such as a mixture of gasoline and air. It is also assumed that suitable exhaust and muffler connections are made with the exhaust port 89. At numeral 91 is shown a suitable ignition device such as, for example, a continuously operating electrical glow plug.

10 Operation is as follows:

15 As the rotor turns, the planetary gears 51 roll on the sun gears 53, thus causing the slider-crank linkages constituted by gudgeons 55, 39 and connecting links 57 to reciprocate the vanes 29 in the rotor as it turns. This sweeps the vanes through the various spacings between the 20 rotor 23 and the inner oval form 5 of ring 3.

25 A suction event develops during an angular vane movement A of a given vane, drawing in combustible fuel through port 87, port 87 being sealed off from the exhaust port 89 by the intervening auxiliary blocking rotor 67. A compression event occurs during an angular vane movement B of the same vane and continues until the compression pressure becomes a maximum, at which time the glow plug 91 becomes exposed by said given vane to ignite a compressed charge of combustible. This

30 initiates the explosion event, which at the instant illustrated in connection with two vanes symmetrically spanning center line X-X produces no driving torque because the exposed opposite areas a and a' of these adjacent vanes are equal. However, momentum carries the rotor 35 system clockwise during ignition. Such momentum is provided by the flywheel effect of parts connected with shaft 25, or if necessary, by means of a flywheel attached thereto but not shown, being conventional. Expansion takes place as said given vane moves through angle C.

40 During this movement the leading vane with face b' has an increasing area over that of the adjacent following vane face b until face b' passes the Y-Y axis. After this the difference diminishes and becomes equal as b' passes point 93. Thus upon gas expansion there occurs 45 a net clockwise driving torque upon the rotor. The expansion and torque events continue until a charge between surfaces such as b and b' becomes exposed to the exhaust port, as illustrated at the lower right in FIG. 1. Such exposure first occurs whenever said given vane 50 crosses the point 93.

55 In short, a suction event starts when a leading vane crosses point 95. A succeeding compression event occurs after the next trailing vane crosses this same point 95. Compression then follows until the first-named leading vane arrives at point 97, at which location its succeeding trailing vane is symmetrically positioned with respect to the short axis of the oval on the vertical center line X-X. After that, expansion occurs between the adjacent vanes until the leading vane reaches point 93. After this, the 60 stated exhaust event occurs.

65 It will be apparent that the point 95 is chosen so that after the trailing one of a pair of vanes passes this point, enlargement of the space between that pair of vanes ceases and the space therebetween thereafter reduces in volume until said pair of vanes symmetrically spans center line X-X. The point 93 is chosen so that it is crossed by a vane at the time maximum volume occurs between a pair of vanes operating in the angular range C.

70 From the above it will be seen that, since there is a positive control of the reciprocations of the vanes by the slider-crank mechanisms, centrifugal force is prevented from driving the outer margins of the vanes into forcible sliding contact with the inner surface 5 of the ring 3. Only the sealing means in the vane slots are subject to

such forces. Since the weights of these are considerably less than the total weights of the vanes, only a small amount of rubbing friction is encountered between the seals and the surface 5.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A rotary engine comprising a radially slotted main rotor assembly, slidable vanes in the slots, fixed sun gear means, planetary gear means mounted on the rotor assembly and meshing with the fixed sun gear means, a slider-crank means connecting each planetary gear with a vane to be reciprocated thereby to move the margins of the vanes in a predetermined trajectory, a casing surrounding the rotor and the vanes and having an inner surface formed along said trajectory, said casing having intake and exhaust ports, a blocking means in the casing located tangentially to the rotor and separating the intake port from the exhaust port, the shape of said trajectory being such as to produce upon rotation of the rotor in the casing expanding and contracting spaces between the casing, rotor and pairs of vanes, the number of vanes and gear-driven slider crank assemblies being six and the tooth ration between each planetary gear means and the sun gear means being 1:2, whereby said trajectory is of oval form, said blocking means being in the form of an auxiliary rotor located on a short axis of said oval form between the intake and exhaust ports which are located on opposite sides of said axis, the auxiliary rotor having a surface operating tangentially to the outer surface of the main rotor and being gear-driven therefrom, said auxiliary rotor including slot means adapted to pass margins of the vanes moving with the main rotor.

2. A rotary engine according to claim 1, wherein the tooth ratio in the gear drive between the rotors, and the number of slots in the auxiliary rotor, are such that passage of each successive vane margins past the auxiliary rotor is accommodated.

3. A rotary engine according to claim 1, wherein said slot means consists of a pair of opposite slots and the gear drive from the main rotor consists of a gear on the main rotor and a meshed gear on the auxiliary rotor, the tooth ratio of the former to the latter being 3:1.

4. A rotary engine comprising a casing of inside bisymmetrical oval shape, said shape having intersecting long and short axes, a main rotor in the casing symmetrically formed for opposed small spacings with respect to said oval shape on the short axis and for opposed larger spacings on the long axis, an auxiliary rotor carried near one end of the short axis and extending across the adjacent close spacing into tangent relationship with the main rotor, intake and exhaust pockets communicating with the outside of the casing on opposite sides of said auxiliary rotor, sun gear means surrounding the intersection of said axes and attached to the casing, a number of planetary gear means rotatably mounted upon the main rotor and meshing with said sun gear means respectively, a number of substantially radially slidable vanes in the main rotor equal in number to said number of planetary gear means, slider-crank means connecting each planetary gear means with a vane to reciprocate the same for controlled positive motion of its end in an oval trajectory closely paralleling the inside oval shape of the casing, a gear drive connecting the main and auxiliary rotors consisting of a drive gear connected with the main rotor meshed with a driven gear on the auxiliary rotor, said auxiliary rotor being provided with a number of recesses

adapted to pass vane ends during their movements past said auxiliary rotor.

5. A rotary engine comprising a casing of inside bisymmetrical oval shape, said shape having intersecting long and short axes, a circular main rotor in the casing closely spaced with respect to said oval shape at two points on the short axis and less closely spaced at two points on the long axis, a circular auxiliary rotor carried by the casing on said short axis and extending across one of the two close spacings and into tangent relationship to the main rotor, intake and exhaust pockets communicating with the outside of the casing on opposite sides of said auxiliary rotor, sun gear means surrounding the intersection of said axes and attached to the casing, several planetary gear means rotatably mounted upon the main rotor and meshing with said sun gear means, a number of radially slidable vanes in the main rotor equal in number to the number of planetary gear means, slider-crank means connecting each planetary gear means with a vane to reciprocate the same for controlled positive motion of its end in an oval trajectory closely paralleling the oval inside shape of the casing, a gear drive connecting the main and auxiliary rotors consisting of a drive gear on the main rotor meshed with a driven gear on the auxiliary rotor, said auxiliary rotor being provided with a number of recesses adapted to pass vane ends during their movements past said auxiliary rotor.

6. A rotary engine according to claim 5, wherein the number of connected vanes and planetary gear means is six and the tooth ratio between each planetary gear means and the sun gear means is 1:2.

7. A rotary engine according to claim 6, wherein the number of recesses in said auxiliary rotor is two, and wherein the tooth ratio of the drive gear on the main rotor to the driven gear on the auxiliary rotor is 3:1.

8. A rotary engine according to claim 5, including ignition means located in the casing at a part of the oval shape adjacent said short axis.

9. A rotary engine according to claim 5, including ignition means located in the casing at a part of the oval shape adjacent said short axis and on its side corresponding to the side on which the exhaust pocket is located with respect thereto.

10. A rotary engine comprising a casing of bisymmetrical oval interior shape having perpendicular short and long axes, a substantially circular main rotor therein forming therewith two crescent-shaped spaces on opposite sides of the short axis, said crescent shapes joining one another through narrow spaces extending across said short axis, an auxiliary blocking rotor on the short axis in tangent relation with the main rotor and blocking one of said narrow spaces, reciprocating vanes in the main rotor, driving mechanisms for said vanes, planetary gear means adapted to actuate said driving mechanisms upon main rotor rotation to reciprocate the vanes to sweep through said spaces, at least one slot in the auxiliary rotor adapted to pass vane ends during main rotor movements, an intake pocket connecting with one end of one crescent shape adjacent one side of the auxiliary rotor, an exhaust pocket connecting with the adjacent end of the other crescent shape on the other side of the auxiliary rotor, and firing means in the casing connected adjacent to the opposite end of the last-named crescent shape and on that side of the short axis upon which said exhaust pocket is located.

11. A rotary engine comprising a radially slotted main rotor having axially opposite recesses containing pairs of coaxially aligned gear pins supporting pairs of planetary gears, the latter carrying coaxially aligned drive pins, a slidable vane in each slot having opposite coaxial driven pins, a margin of each vane extending from said rotor, pairs of connecting links articulating said pairs of driving and driven pins, an auxiliary rotor carrying a driven gear and having slot means therein, a drive gear on the main rotor meshed with said driven gear on the auxiliary

rotor, said gears being adapted to coordinate movements of the rotors to accommodate in the slot means of the auxiliary rotor margins of vanes which successively pass said auxiliary rotor, a casing supporting said auxiliary rotor and surrounding said main rotor, said casing having an inside oval shape in the plane of movements of said slidable vanes, said main rotor and said casing having closely fitting circular shapes flanking the portions of the main rotor in which said vanes reciprocate and a pair

of sun gears affixed to said casing and meshing with respective members of said pairs of planetary gears.
